VENETIAN BLIND

William Wade, Chicago, and Edwin North, Rockford, Ill., assignors to National Lock Company, Rockford, Ill., a corporation of Delaware

Application January 28, 1937, Serial No. 122,803

5 Claims. (Cl. 156—17)

This invention relates to Venetian blinds, and particularly to novel means for supporting the blind slats from a top rail or carriage.

One of the important objects residing in the invention is the provision of flexible slat supporting and controlling members in the form of cords or the like and means for attaching the supporting members to the several slats and for maintaining certain others of the flexible members in proper operating relation to the first mentioned flexible members.

A further object of the invention is the provision of a Venetian blind which is relatively quiet in operation or when subjected to unusual vibration such as might be found in Pullman cars and the like.

Still another object is the provision of novel slat supporting means of an extremely flexible nature and adapted for novel attachment to the blind slats and top rail or carriage.

Other objects and novel aspects of the invention will appear as the following description proceeds in view of the annexed drawing, in which:

25 Fig. 1 is a front elevation of a blind structure utilizing the novel slat supporting means of the present invention;

Fig. 2 is an enlarged perspective fragment of the carriage and means for attaching the flexible elements to the carriage and to a slat;

Fig. 3 is a fragmentary vertical section taken laterally through the carriage and a slat and viewed along lines 3—3 of Fig. 1;

Fig. 4 is an enlarged perspective of the means 35 for attaching the flexible supporting elements to the edge of a slat, while

Fig. 5 is an elevational detail of a supporting pair including one chain and one fabric cord.

In Fig. 1 herein we have chosen for purposes 40 of illustration a type of Venetian blind structure particularly shown and described in our co-pending application Serial No. 122,793, filed January 28, 1937, to which reference may be had for a more detailed description of certain 45 of the operating and control mechanisms hereinafter referred to.

In general the above mentioned blind structure includes a plurality of slats 10 suspended in spaced relation between pairs of cords 12, which in turn depend from a pivotable carriage 14 supported by and between a pair of brackets 15 and 16 secured in the upper corner portions 50 of a window casing 18 behind a valance plate 20.

The pairs of suspending cords 12 each include 55 a front cord 12' and a rear cord 12'' (Figs. 2 and

3), the front cord being attached at its upper extremity to the bottom of the carriage 14 by means of an eyelet sleeve 22 crimped onto the end of the cord and having a stay pin 24 passed through the eyelet portion thereof and bent into 5 U-shape with its free end portions diverged over the edges of an opening 25 in the bottom of the carriage, these diverged ends of the pin being secured from displacement by bent over ears 26 which are punched out of the side walls of the 10 carriage 14 and bent over onto the pins.

The lowermost ends of these same outer cords 12' are provided with eyelet sleeves 22' which engage cleats 11 secured to the bottommost slat 13, the cleats having eyelets or loops 11' which 15 pass through the eyelet portion of the sleeve so that the cord is pivotally attached at its lower extremity to the edge of this lower slat.

Each of the front cords 12' is also attached to the longitudinal edges of each of the intermediate slats 10 by means of a special clip 20 shown in Fig. 4. This clip 30 is in the form of an elongated metal strip bent back upon itself to have opposite upper and lower finger portions each provided with an outwardly turned lip 31 25 and having a bight portion 32 through which a wire attaching loop 33 is passed for attachment to the front cord 12'.

The loop 33 has its free end portions bent back upon themselves to provide overlying axially aligned eyelets 34 through which the cord passes and which may be crimped or pressed so as to tightly grip the cord and prevent the displacement of the loop therealong.

The clip proper may have a crimp 36 (Fig. 3) 35 formed in the lower finger thereof and adapted to press into a slot 37 formed in the bottom surface of the slat 10, this type of clip structure being particularly set forth in our co-pending application Serial No. 122,795, filed January 28, 40 1937, for a clip. This construction facilitates slipping the clip onto the edge of the slat, and likewise removing the clip so that the slats may be cleaned or removed for purposes of repair 45 and the like.

The inner cords 12'' are not attached to each of the intermediate slats but only to the lowermost slat 13 at their lower extremities, thereafter passing upwardly through the main opening of the loops 33 and on upwardly through 50 collars 38 in the bottom wall of the carriage 14, from whence they pass over twin rollers 40 (Figs. 2 and 3) and through an axial pay-hole 42 in the pivotal mounting of the roller housing 44 in the end wall 45 of the carriage. Within the hous- 55

ing 44 is disposed a vertical roller 46, the periphery of which is tangential with the center of the pay-hole 42, and forwardly of the roller 46 is a horizontal roller 48 over which the several rear cords 12" pass from the vertical roller 46 out through the bottom of the housing 44 for engagement with a union clip 50.

The clip 50 is a stamping having a hemispherical cord seat 52 with a bottom opening through which the knotted extremity 9 of the pulley cord 8 extends. The cord seat 52 is joined by ribs 53 to a widened upper body portion bent back upon itself to provide a bight 54 through which an oblong wire loop 55 is passed and which in turn engages a plurality of eyelet sleeves 22" crimped onto the upper ends of the back cords 12" as they issue from the bottom of the roller housing 44. In this manner a unitary pull cord 8 is attached to the several rear cords 12" so that the latter 10 may be raised simultaneously for the purpose of raising the lower slat 13 against the intermediate slats 10 so as to fold the latter in gathered relation up under the carriage 14. As an appreciable pull is exerted upon the cord 8 in this operation, it is found desirable to secure the overlying end 50' of the widened body portion of the union clip to the main body portion by means of a screw 56 threaded into the main body portion 15 of the clip.

It will thus be evident that we have provided a novel blind structure in which the blind slats are supported between pairs of flexible members in the form of cords, and additionally we have provided novel means for attaching these cords 20 to the several slats and also to the operating mechanisms of the structure. It has heretofore been common practice to support the blind slats by means of fabric tapes, and various devices 25 have been arranged for manipulating these tapes in such manner as to tilt the slats and otherwise control the operation of the blind, but these tapes are not suited to the type of control mechanism disclosed herein and with which the present novel slat supporting means is intended to be used.

In applicants' co-pending case first mentioned above, the supporting means is in the form of light chains, and while for most purposes these chains are very desirable and represent an important advance in the art, they have a tendency 30 to create noise when the blind structure is vibrated or shaken to any considerable degree, as, for example, in installations on rolling stock including Pullman cars and the like.

In the form of arrangement shown in Fig. 5, we employ a simple outer chain 12''' such as disclosed by our above-mentioned co-pending cases, while the companion element is a fabric cord 12⁴. By this arrangement the nesting or bunching of the slats is quietly effected as the cord 12⁴ moves over roller 40', and this cord, being attached only at its extremities, does not create any disturbing vibratory noise or chatter against either its companion chain or the slats.

By our present invention we have retained all 35 of the desirable features of the chain type of suspending means and at the same time eliminated the possibility of noise from excessive vibration

by the employment of cord supporting elements such as the cords 12' and 12" herein, and the special attaching devices in the form of the eyelet sleeves 22 and the clip loops 33, together with the common or union clip 50, and while changes 5 may be made in the specific illustrative structure described herein, we do not intend to be limited to such details except as may be provided in the appended claims.

Having thus described our invention, what we 10 claim as new and desire to protect by Letters Patent is:

1. Means for attaching blind slats to thin supporting cords, said means including a removable attaching member having a bight portion and adapted to fit over the edge of a slat, and a looped member passing through said bight portion and having free end portions bent back upon themselves to form axially aligned and substantially closed loops firmly embracing said cord, the main 20 loop opening of said looped member being large enough to permit free passage therethrough of another cord similar to said first-mentioned cord.

2. Means for attaching blind slats to thin supporting elements, said means including an attaching clip having a bight portion and adapted to slip over the edge of a slat, a loop member passed through said bight portion and having free end portions wound around said supporting element and firmly gripping the latter so as to 30 support the loop in a plane substantially normal thereto.

3. Slat attaching means for Venetian blind structures, said means including a clip adapted to fit edgewise onto a slat and a loop member pivotally engaging said clip along an axis parallel to the edge of said slat, said loop having free end portions turned back in opposite directions and firmly embracing a filamentary supporting element so as to support said loop at substantially 40 right angles to said element.

4. In Venetian blinds having slats and supporting cords therefor, means for attaching the slats to the cords and including a U-shaped clip member adapted to fit over the edge of a slat 45 and having a bight portion normally parallel to the edge of the slat, a loop member pivotally engaging said bight portion of the clip and having its opposite free end portions turned back upon itself to provide substantially aligned openings through which said cord is extended, said edge portions being crimped into substantially rigid engagement with said cord so as to substantially prevent relative movement of the cord and said loop.

5. Means for attaching supporting cords to Venetian blind slats, said means including a loop member having free end portions turned back upon themselves around said cord and grippingly engaging the latter, and means pivotally attaching said loop to an edge portion of said slat with said loop normally lying in the plane of the slat and the opening in said loop being large enough to provide for the free passage of a cord element similar to said first-mentioned cord.
